FILE FOR PAPERS AND THE LIKE

Louis L. Kearney, Oakland, Calif., assignor to
 American Smelting and Refining Company,
 New York, N. Y., a corporation of New Jersey

Application September 8, 1941, Serial No. 409,981

12 Claims. (Cl. 129—25)

My invention relates to letter files and more particularly to an improved folder for filing letters, reports and the like.

The procedure generally followed in connection with conventional filing systems is to initially provide a temporary folder for all of the papers relating to the same subject matter or for those which are to be filed under separate headings. After the file is completed, that is to say, after the folder is filled and the particular file is to be closed, the papers are removed and transferred to another folder or jacket and stored.

It will be appreciated that in filing systems of the above noted character the temporary folders are very often subjected to considerable handling prior to the time the papers are removed and stored, for the reason that they form the current files. In order to withstand ordinary expected usage and handling during this period, it has been suggested that heavier folders be used for the temporary files, the papers being attached to a folder at one side thereof by means of metal fasteners having a removable clip arrangement. When the file is complete and the papers are to be permanently filed or stored, the papers and clip portion of the fastener are removed as a unit and transferred to a lighter-weight folder.

While the above suggested method is satisfactory from the standpoint of economy of folder cost, since the heavier and more expensive folder can be repeatedly used for a considerable period of time, it has been found that the economies thus effected are offset to an appreciable extent, by reason of the additional time required to transfer the papers from one folder to another preparatory to permanent filing or storage.

In accordance with the present invention, the folder in which the papers are to be permanently filed, is detachably connected to the temporary folder interiorly thereof, whereby the folder, papers and clip portion of the metal fastener may be removed as a unit. By means of the novel construction and arrangement of the folders of the present invention, the papers are filed directly in the folder which is to form the permanent file and when the file is complete or is to be closed, it is only necessary to detach the folder and contents from the outer cover formed by the temporary folder.

An object of my invention is to provide an improved folder for filing letters, reports and the like.

Another object of my invention is to provide

an improved folder arrangement for use with filing systems of the character wherein the papers are initially filed in a temporary folder and on completion of the file are thereafterwards transferred to another folder and permanently filed.

Yet another object of my invention is to provide an improved filing arrangement wherein the folder in which the papers are to be permanently filed is detachably connected to the temporary folder.

Still another object of my invention is to provide an improved folder constructed and arranged whereby the permanent file folder and contents can be quickly and easily removed as a unit from the temporary folder.

A further object of my invention is to provide an improved file folder arrangement whereby substantial economies in folder costs and filing time are effected.

With these and other objects in view, which may be incident to my improvements, the invention consists in the parts and combinations to be hereinafter set forth and claimed, with the understanding that the several necessary elements, comprising my invention may be varied in construction, proportions and arrangement, without departing from the spirit and scope of the appended claims.

In order to make my invention more clearly understood, I have shown in the accompanying drawings means for carrying the same into practical effect, without limiting the improvements in their useful applications to the particular constructions, which for the purpose of explanation, have been made the subject of illustration.

In the drawings:

Figure 1 is a perspective view of a folder arrangement of the present invention showing the inner and outer folders prior to assemblage.

Fig. 2 is a perspective view of the inner folder after assembly, showing a file of papers, correspondence or the like.

Fig. 3 is a sectional view through the detachable fastener used to secure the folders and papers to be filed.

Fig. 4 is a perspective view of a portion of the rear of the inner folder, in the vicinity of the fastener.

Fig. 5 is a perspective view of a portion of the folder cover of the inner folder after the folder and filed contents have been removed from the outer folder.

Fig. 6 is a perspective view of a modification of the folder arrangement shown in Fig. 1,

Fig. 7 is a perspective view of a portion of the inner folder, in the vicinity of the fastener; and

Fig. 8 is a perspective view of a portion of the folder cover of the inner folder and filed contents after the folder and contents have been removed from the outer cover folder.

Referring to the drawings and more particularly to Fig. 1, the improved folder arrangement comprises an outer folder having cover members 1 and 2, joined by means of a flexible binding 3 10 of fabric or other suitable material, adhesively secured to the marginal edges of the cover members. The outer folder forms a temporary cover for the inner folder and the cover members 1 and 2 thereof, are preferably formed from relatively heavy paper stock in order to withstand routine handling incident to normal use.

The inner folder, designated generally by numeral 4, may be formed from a single piece of sheet material, the sheet being bent along a fold line 5 to form cover members 6 and 7. In the position shown in Fig. 1, cover member 7 is reversely folded upon cover 6, that is to say, cover 7, when the folder is closed, is folded about line 5 directly over cover member 6 with identification tab 8 projecting outwardly from the underneath cover.

In order to detachably secure the folders together, there is provided a two-part fastener of conventional construction, comprising a portion 9 which is permanently attached to cover member 2 of the outer folder and removable portion designated generally by numeral 10, attached to cover member 6 of the inner folder. The removable portion of the fastener is in the form of a clip having a base portion 11, (Fig. 4) prong members 12 and a locking plate 13, the prong members being adapted to be bent downwardly and maintained in contact with the locking plate by means of suitable loops or rings 14, in accordance with accepted practice.

For the purpose of permitting access to the rear portion or base 11 of the removable part of the fastener, that is, to permit engagement of this portion of the fastener with portion 9 attached to the outer folder when the covers of the inner folder are folded in the filing position, as shown in Fig. 1, a slot or opening is formed in cover 7, opposite the fastener. As will be seen in Fig. 4, cover member 7 in the vicinity of the fold line 5, is provided with a rectangular shaped slot or cut-out portion 15, by removing a portion of the body of the cover along two sides and at one end, thus forming a flap 16, adapted to fold along its line of attachment 17, to the body portion of the cover, as will be described more fully hereinafter.

In preparing the folders for assembly, preparatory to filing papers and the like therein, portion 9 of the fastener is permanently attached to cover 2 of the outer folder, cover 6 of the inner folder is formed with openings or apertures 18 to receive prongs 12, and cover member 7 is cut out to provide slot 15 and flap 16, as shown in Fig. 4. After the fastener portions have been attached to the respective covers, as above described, the inner folder cover 7 is turned backwardly upon cover 6, (Fig. 1) with flap member 16 in the open position, that is to say, extending outwardly away from slot 15 and lying substantially flat between the covers, as shown by its dotted line position in Fig. 1.

It will thus be seen that base 11 of the removable portion of the fastener is then exposed through slot 15 and that the inner folder 4 can readily be attached to the outer cover by merely

sliding base 11 of fastener portion 10 into engagement with portion 9 attached to the outer cover.

Referring to Fig. 2, the inner folder is shown in assembled position. The papers, correspondence and the like 19, are filed as usual by inserting the ends of the paper over prongs 12 of the detachable portion of the fastener. When the file is complete, the inner folder 4 is removed from the outer cover and cover member 7 turned back to its normal position as the front cover of the folder. The folder and contents can then be filed as a unit, it being understood that the outer cover is intended for re-use as a temporary folder for other files.

In order to prevent prongs 12 of adjacent folders from becoming entangled when the permanent folders are filed or stored in filing cabinets, flap 16 is provided with sealing means in the form of adhesive tape or the like whereby the flap may be sealed in closed position after the folder has been removed from the outer cover. As shown in Fig. 5, the flap member is covered with a piece of adhesive tape 20, the marginal edges 21 of which extend outwardly beyond the adjacent edges of the flap. After the inner folder 4 has been removed from the cover folder, the flap can be sealed in closed position to provide a substantially smooth continuous surface on the exterior of the folder.

The folder arrangement above described is designed particularly for use in connection with the filing of letter size correspondence, reports and the like. The basic conception of the invention, however, is also applicable to other types of folders, for example, legal size folders wherein the cover members are hinged at the end portions of the folders.

Referring to Fig. 6, there is shown a legal size folder arrangement comprising an outer folder having covers 22 and 23 joined at their top edges by means of fabric or other flexible material 24, adhesively secured to the marginal edges of the respective cover folders. The inner folder 25, like folder 4 of Fig. 1, is formed from a single piece of sheet material of comparatively lighter weight than the stock from which the outer folder is made, the sheet being folded along line 26 to provide cover members 28 and 29. In the position shown in Fig. 6, cover member 29 is reversely folded on cover 28, with file identification tab 30 projecting outwardly from the top cover.

The fastener portions by means of which the folders are detachably secured are attached to the folders as heretofore described, that is, portion 9 is permanently attached to cover 23 and the removable portion 10 is attached to cover 28 of the inner folder. In order to permit sliding engagement of the fastener parts, the top edge of cover 29 is formed with a recessed or slotted portion by turning back a portion of the edge against the under surface 31 of the cover, as shown in Fig. 7. The edges of flap 32 may be provided with adhesive tape or other sealing means 33, (Fig. 8) so that the flap can be sealed in closed position after the inner folder and filed contents 34 are removed from the outer folder.

The folders are prepared for filing, that is to say, for the reception of the papers to be filed, in substantially the same manner as the folder arrangement of Fig. 1. Assuming that the fastener portions 9 and 10 have been attached to the proper covers of the inner and outer folders and that the top edge of cover 29 has been slotted, cover 29 is reversely folded on cover 28 thereby

exposing the base portion of the removable fastener so that it can slidably engage with portion 9. The inner folder 25 is then positioned within the outer cover with the fastener portions in locking engagement. After the file is complete, the inner folder and filed contents are removed, (Fig. 7) flap 32 being straightened out and sealed in normal extended position, as shown in Fig. 8.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. A file for papers, correspondence and the like comprising an outer cover folder and an inner folder, means for detachably securing the folders together comprising a fastener having a base portion permanently attached to one of the outer folder covers and a portion adapted for sliding engagement with said base, attached to one of the covers of the inner folder, said latter portion of the fastener having bendable prong members thereon adapted to receive the papers to be filed, the other cover member of said inner folder having a cut-out portion therein formed by turning back a portion of the body upon itself, whereby when said cover is reversely folded upon the cover to which the paper receiving portion of the fastener is attached, said fastener portion is in alinement with and extended through said cut-out portion to be slidably engageable with the base portion of the fastener.

2. A file for papers, correspondence and the like comprising an outer folder having a pair of cover members formed from relatively heavy paper and an inner folder formed from paper of comparatively lighter weight, means for detachably securing the folders together with one of the cover members of the inner folder reversely folded upon the other cover of said folder, comprising a fastener having a base portion permanently attached to one of the outer folder covers and a portion adapted for sliding engagement with said base attached to one of the covers of the inner folder, said latter portion of the fastener having bendable prong members thereon adapted to receive the papers to be filed, the other cover member of said inner folder having a cut-out portion therein formed by turning back a portion of the body upon itself, whereby when said cover is reversely folded upon the cover to which the paper receiving portion of the fastener is attached, said fastener portion is in alinement with and extended through said cut-out portion to be slidably engageable with the base portion of the fastener.

3. A file for papers, correspondence and the like comprising an outer cover folder and an inner folder, means for detachably securing the folders together with one of the cover members of the inner folder reversely folded upon the other cover of said folder, comprising a fastener having a base portion permanently attached to one of the outer folder covers and a portion adapted for sliding engagement with said base attached to one of the covers of the inner folder, said latter portion of the fastener having bendable prong members thereon adapted to receive the papers to be filed, the other cover member of said inner folder having a cut out portion

therein formed by turning back a portion of the body upon itself, whereby when said cover is reversely folded upon the cover to which the paper receiving portion of the fastener is attached, said fastener portion is in alinement with and extended through the opening of said cut-out to be slidably engageable with the base portion of the fastener.

4. A file for papers, correspondence and the like comprising an outer cover folder and an inner folder, means for detachably securing the folders together comprising a fastener having a base portion permanently attached to one of the outer folder covers and a portion adapted for sliding engagement with said base attached to one of the covers of the inner folder, said latter portion of the fastener having bendable prong members thereon adapted to receive the papers to be filed, the other cover member of said inner folder having an opening therein in the vicinity of its fold line opposite the removable portion of the fastener, whereby when said cover is reversely folded upon the cover to which the paper receiving portion of the fastener is attached, said fastener portion is in alinement with and extended through said opening to be slidably engageable with the base portion of the fastener.

5. A file for papers, correspondence and the like comprising an outer cover folder and an inner folder, means for detachably securing the folders together comprising a fastener having a base portion permanently attached to one of the outer folder covers and a portion adapted for sliding engagement with said base attached to one of the covers of the inner folder, said latter portion of the fastener having bendable prong members thereon adapted to receive the papers to be filed, the other cover member of said inner folder having an opening therein in the vicinity of its fold line opposite the removable portion of the fastener, whereby when said cover is reversely folded upon the cover to which the paper receiving portion of the fastener is attached, said fastener portion is in alinement with and extended through said opening to be slidably engageable with the base portion of the fastener, a closure member for closing said opening and means associated with said member to seal it in closed position after the inner folder has been removed from the outer cover folder.

6. A file for papers, correspondence and the like comprising an outer cover folder and an inner folder, means for detachably securing the folders together comprising a fastener having a base portion permanently attached to one of the outer folder covers and a portion adapted for sliding engagement with said base, attached to one of the covers of the inner folder, said latter portion of the fastener having bendable prong members thereon adapted to receive the papers to be filed, the other cover member of said inner folder having an opening therein in the vicinity of its fold line opposite the removable portion of the fastener, whereby when said cover is reversely folded upon the cover to which the paper receiving portion of the fastener is attached, said fastener portion is in alinement with and extended through said opening to be slidably engageable with the base portion of the fastener, a closure member for said opening comprising a flap formed from the body of the cover attached thereto along one edge, and means associated with said flap to seal it in closed position after

the inner folder has been removed from the outer cover folder.

7. A file for papers, correspondence and the like comprising an outer folder having a pair of cover members formed from relatively heavy paper and an inner folder formed from paper of comparatively lighter weight, means for detachably securing the folders together with one of the cover members of the inner folder reversely folded upon the other cover of said folder, comprising a fastener having a base portion permanently attached to one of the outer folder covers and a portion adapted for sliding engagement with said base, attached to one of the covers of the inner folder, said latter portion of the fastener having bendable prong members thereon adapted to receive the papers to be filed, the other cover member of said inner folder having an opening therein in the vicinity of its fold line opposite the removable portion of the fastener, whereby when said cover is reversely folded upon the cover to which the paper receiving portion of the fastener is attached, said fastener portion is in alinement with and extended through said opening to be slidably engageable with the base portion of the fastener.

8. A file for papers, correspondence and the like comprising an outer folder having a pair of cover members formed from relatively heavy paper and an inner folder formed from paper of comparatively lighter weight, means for detachably securing the folders together with one of the cover members of the inner folder reversely folded upon the other cover of said folder, comprising a fastener having a base portion permanently attached to one of the outer folder covers and a portion adapted for sliding engagement with said base, attached to one of the covers of the inner folder, said latter portion of the fastener having bendable prong members thereon adapted to receive the papers to be filed, the other cover member of said inner folder having an opening therein in the vicinity of its fold line opposite the removable portion of the fastener, whereby when said cover is reversely folded upon the cover to which the paper receiving portion of the fastener is attached, said fastener portion is in alinement with and extended through said opening to be slidably engageable with the base portion of the fastener, a closure member for closing said opening and means associated with said member to seal it in closed position after the inner folder has been removed from the outer cover folder.

9. A file for papers, correspondence and the like comprising an outer cover folder and an inner folder, means for detachably securing the folders together comprising a fastener having a base portion permanently attached to one of the outer folder covers and a portion adapted for sliding engagement with said base, attached to one of the covers of the inner folder, said latter portion of the fastener having bendable prong members thereon adapted to receive the papers to be filed, the other cover member of said inner folder having its top edge folded back upon its self, whereby when said cover is reversely folded upon the cover to which the paper receiving portion of the fastener is attached, said fastener portion is in alinement with and extended through the opening formed by said folded back edge to be slidably engageable with the base portion of the fastener.

10. A file for papers, correspondence and the

like comprising an outer cover folder and an inner folder, means for detachably securing the folders together with one of the cover members of the inner folder reversely folded upon the other cover of said folder, comprising a fastener having a base portion permanently attached to one of the outer folder covers and a portion adapted for sliding engagement with said base, attached to one of the covers of the inner folder, said latter portion of the fastener having bendable prong members thereon adapted to receive the papers to be filed, the other cover member of said inner folder having its top edge folded back upon itself, whereby when said cover is reversely folded upon the cover to which the paper receiving portion of the fastener is attached, said fastener portion is in alinement with and extended through the opening formed by said folded back edge to be slidably engageable with the base portion of the fastener.

11. A file for papers, correspondence and the like comprising an outer cover folder and an inner folder, means for detachably securing the folders together with one of the cover members of the inner folder reversely folded upon the other cover of said folder, comprising a fastener having a base portion permanently attached to one of the outer folder covers and a portion adapted for sliding engagement with said base, attached to one of the covers of the inner folder, said latter portion of the fastener having bendable prong members thereon adapted to receive the papers to be filed, the other cover member of said inner folder having its top edge folded back upon itself, whereby when said cover is reversely folded upon the cover to which the paper receiving portion of the fastener is attached, said fastener portion is in alinement with and extended through the opening formed by said folded back edge to be slidably engageable with the base portion of the fastener, and means associated with said turned over portion to seal it in normal extended position in the plane of the cover, after the inner folder has been removed from the outer cover folder.

12. A file for papers, correspondence and the like comprising an outer folder having a pair of cover members formed from relatively heavy paper and an inner folder formed from paper of comparatively light weight, means for detachably securing the folders together with one of the cover members of the inner folder reversely folded upon the other cover of said folder, comprising a fastener having a base portion permanently attached to one of the outer folder covers and a portion adapted for sliding engagement with said base attached to one of the covers of the inner folder, said latter portion of the fastener having bendable prong members thereon adapted to receive the papers to be filed, the other cover member of said inner folder having its top edge folded back upon itself, whereby when said cover is reversely folded back upon the cover to which the paper receiving portion of the fastener is attached, said fastener portion is in alinement with and extended through the opening formed by said folded back edge to be slidably engageable with the base portion of the fastener, and means associated with said turned over portion to seal it in the normally extended position in the plane of the cover, after the inner folder has been removed from the outer folder cover.

LOUIS L. KEARNEY.
